COOKING RANGE DOOR MOUNTING

Kenneth S. Jenson, Wisconsin Rapids, Wis., assignor to Preway Inc., Wisconsin Rapids, Wis., a corporation of Wisconsin

Application May 23, 1950, Serial No. 163,694

3 Claims. (Cl. 126—191)

This invention relates to a hinge connection and a spring counterbalance for the door of a cooking range.

The main objects of this invention are to provide an improved mounting for the door of a cooking range which is designed to swing between positions which are substantially vertical and horizontal; to provide improved stop means for limiting the swing of the door to, and supporting it in, a horizontal open position; to provide improved counterbalancing means for yieldingly resisting opening movement of the door and facilitating the closing thereof; and to provide an improved hinge, stop, and counterbalancing means of this kind whereby the door is swingably mounted on the range with but a single fastening means for each hinge connection.

A suggestive embodiment of this invention is set forth in the accompanying drawings wherein—

Figure 1 is a front elevation of the open front of the cooking compartment of a range which is equipped with the present hinged door and counterbalancing spring therefor;

Fig. 2 is a fragmentary side elevation of the cooking compartment whose open door is shown in section;

Fig. 3 is a fragmentary vertical cross section, taken on line 3—3 of Fig. 1, the door being shown in its closed position;

Fig. 4 is a detail in section of the hinge mounting for the door which is shown in its open position;

Fig. 5 is a vertical elevational view, taken on the plane of line 5—5 of Fig. 3; and

Fig. 6 is a detail in section, taken on line 6—6 of Fig. 4.

The cooking range herein shown comprises a frame 8 mounting a vertically swinging oven door D with the aid of a pair of hinge plates H, a spring S and a tension rod R.

The range frame 8 is conventional in that it provides for several compartments each having a front opening wherewith is associated a suitable door. In the drawing only so much of the frame 8 is shown as is necessary to illustrate an oven 9 with a bottom 10 and adjustable shelves 11 thereover and above a broiler compartment 12, the opening o of the oven being closed by a door D. At the front, laterally of each side of the opening o, the frame is slotted at 15 to receive therethrough one of the hinge plates H and also a stop arm A which cooperates therewith in a very special manner.

The door D may be of usual construction with sheet metal plates 17 and 18 in spaced relation and with an intervening stiffener plate 19 which is marginally offset to provide a flange 20 for bonding to the plates 17 and 18. Each hinge plate H has its opposite ends transversely offset, and one of its ends is forked to provide spaced ears 21 and 22. The stop arms A extend arcuately and each is joined to an elongated base 23 one end of which laps the ear 21 of the hinge plate H to be connected thereto by a pivot pin 24. At its opposite end the hinge plate is apertured to receive a fastener, as will be presently described, along one side it is also provided with a transversely extending lug 25, and beyond its extremity there is further extended a lug 26 ending in a laterally turned flange 27.

Each stop arm base 23 is positioned interiorly of the door D between the plates 17 and 18 along one side of the stiffener plate 19. Near its opposite ends each base 23 is formed with laterally turned ears 28 and 29 the former of which is provided with a hook 30 which engages an offsetting corner of the stiffener plate 19 (see Fig. 5). The other ear 29 overlies the stiffener plate at

2

a point adjacent one edge of the door D. The inner extremity of the base 23 of the stop arm A is pivotally connected to the ear 21 of the hinge plate H by the pin 24 already described.

Each stop arm A which is concentric with the pivot pin 24 traverses a fixed arcuate path closely adjacent its associated hinge plate H. The outer end of the arcuate stop arm A is provided with a radial shoulder 33 which engages the lug 25 to limit outward swinging of the door D and hold it firmly in its horizontally disposed position.

The counterbalancing spring S may be of the coiled tension type having at one end a hook 35 for engaging a stud 36 attached to the stop arm A near its free end, and with a hook 37 at its opposite end for connection with

the tension rod R. Near one end this rod is bowed outwardly at 39 and then terminates in a transversely extending loop 40. The rod bow 39 is extended through an aperture 41 in the base of the stove frame 8 so as to present its terminal loop inwardly opposite the lower end of the spring S with whose hook 37 it is engaged.

At its upper end the rod R is angled forwardly at 42 for confinement behind a flange 43 extending vertically from the frame 8 where its extremity is free to seat in a socket 45 in a horizontal flange 46 on the frame, thereby to secure the tension rod R in a fixed position.

The spring S is by this means maintained under tension when secured to the stud 36.

When each hinge plate H is operatively positioned, its ear 22 which is shouldered engages an upstanding ledge

51 at the bottom of the slot 15, and its laterally turned flange 27 at the top engages a slot 52 in an inner side of the frame 8. Only a single fastening means is then required to operatively secure each assembly of hinge plate H, stop arm A, and counterbalancing spring S, and this may take the form of a screw 53 which is entered through an aperture 54 in the hinge plate H near its top to engage with a tapped hole 55 in the frame 8.

The spring S is maintained under tension to exert a counterbalancing force on the stop arm A and therethrough upon the door as well, so long as the angled end of the tension rod R remains confined in place. When pushed outwardly from behind the flange 43 it is free to swing forwardly thereby to relax the spring S to the point, if need be, of permitting its disconnection from the associated parts preliminary to disassembly thereof and removal of the door from its mounting on the range. The tension rod is, in effect, a bell crank lever fulcrumed to rock and slide on the frame, and because of the ratio in the leverage exerted on the spring, it has a capacity for readily tensioning a powerful spring when the assembly operation is being performed. One such spring will probably suffice as a counterbalance for the ordinary door, but if necessary each hinge plate-stop arm assembly may include a spring S to enhance the tension force of the counterbalance therefor.

In the construction described, each hinge plate H extends downwardly and forwardly to carry at its lower end in front of the frame 8 the pivot pin 24 which constitutes one of the hinges for the door D. The entire load imposed by the door is thereby transmitted through the hinge plate to the frame 8. The lug 27 at its top, when engaged with the slot 52, holds the hinge plate against rotative movement when the door D is operated to open or closed position. The screw 53 is relied upon not to withstand the door load, but to hold the hinge plate in a fixed position on the frame where the ears 21 and 22 and lug 27 are effective to resist all strains.

The hinge plates H are so mounted on the frame as to cooperate effectively with the stop plates A when the radial shoulders 33 thereof are brought into engagement with the lugs 25 (see Fig. 4). When so engaged, each hinge plate H is prevented from tilting in response to the force transmitted thereto from the stop plate A; by reason of the engagement of the lug 27 with the slot 52 the hinge plate is held against forward movement at its top, and at its lower end the shouldered ear 22 engaging with the slot 15 prevents movement of the hinge plate either inwardly or outwardly of the frame so as to maintain the axes of the pins 24 in the fixed position shown. There is furthermore an extended anchorage of the base 23 within the door itself so as to reinforce the latter out-

wardly from its hinge axis when the stop plate A is in engagement with the hinge plate H. In consequence, the door is stiffened in a radial direction along its opposite edges where the stop plates are engaged with the hinge plates so as to be amply sustained in a horizontal position.

I claim:

1. In a cooking range having a frame defining an opening, a pair of hinge plates affixed to the frame, one adjacent each side of the opening and each extending downwardly therefrom and outwardly thereof, the lower end of each hinge plate being disposed outwardly of the frame below its opening, a door for closing the opening in hinge connection with the two hinge plates near their lower end, said frame having slots therein lying in planes substantially normal to the plane of the door when closed and disposed above the bottom of said opening, abutment means near the top of the hinge plates and integral therewith engaging the vertical edge of the slots nearest said door for preventing rocking movement of the hinge plates relative thereto, a single screw fastening element entered through each hinge plate for removable connection with the frame to maintain the hinge plate in operative position thereupon, a pair of stop arms elongated arcuately in concentric relation with the hinge axis of the door and each having an elongated base in connection with the door at widely spaced points radially thereof, each stop arm being disposed adjacent one hinge plate and provided with means coacting therewith when the door has swung outwardly to a horizontal position to provide a stop and sustaining support therefor, a tension spring in connection with one of the stop arms near its free end and extended downwardly therefrom, a vertical tension rod also extended downwardly opposite the spring and forwardly thereof, the lower end of the tension rod being laterally curved through a partial loop to connect with the proximate end of the spring, means on the frame providing a fulcrum whereon the tension rod is rockably and slidably supported at its curved loop portion for movement forwardly at its upper end, and means carried by the frame adjacent the free upper end of the tension rod and below the door for normally confining the tension rod against forward movement whereby its lower end is maintained downwardly to hold the spring under tension.

2. In a cooking range having a frame defining an opening, a door for closing the opening, said frame having slots extending rearwardly from the front of the opening and disposed above the bottom of the opening, a pair of hinge plates secured to the frame, one adjacent each side of the opening and a hinged connection with the door to provide therefor a mounting such that the door may swing between a vertical closed position and a substantially horizontal open position, each hinge plate having at its lower end integral means freely engaging with the frame to derive sustaining support therefrom and being formed near its top with integral abutment means extending laterally to freely enter said slots in the frame and engaging with a vertical edge thereof nearest the front of the frame to hold the hinge plate fixedly against

rocking or sliding movements relative thereto, screw means extended through each hinge plate at a point intermediate of its two points of engagement with the frame, each screw means having its axis in parallelism with the door hinge connection and in threaded connection with the frame to releasably maintain each hinge plate in operative engagement therewith, and an arm in fixed connection with the door having stop means to engage the hinge plate when the door has swung to a substantially horizontal position to provide therefor a sustaining support free of any shearing stress upon the screw means.

3. In a cooking range having a frame defining an opening, said frame having first slots extending rearwardly from adjacent the front of the opening and positioned above the bottom of the opening and second slots disposed beneath the opening, a pair of hinge plates affixed to the frame, one adjacent each side of the opening, and both extending downwardly and outwardly therefrom, each hinge plate having near its bottom a pair of spaced ears one freely receivable in one of said second slots in the frame to engage therewith and derive therefrom a sustaining support for the hinge plate, the other ear being disposed forwardly of the frame and extending downwardly below the opening therein, each hinge plate being formed near its top with a pair of lugs laterally extended in opposite directions, one of the lugs being freely receivable within one of said first slots in the frame to engage the forward vertical edge of the slot whereby to hold the hinge plate fixedly against rocking or sliding movements relative thereto, screw means extended through each hinge plate at a point intermediate of its two points of engagement with the frame and in threaded connection with the frame to releasably maintain each hinge plate in operative engagement therewith, a door in hinged connection with the forward ears of the hinge plates at a point below the opening in the frame, the axes of the screw means and of the door hinged connection being parallel, means affixed to the door and extended rigidly therefrom inwardly and arcuately about the axis of the door hinge, and a stop shoulder on each of said rigid means engageable with the second of said pair of lugs on the adjacent hinge plate when the door has swung open to a substantially horizontal position to maintain the door in said position.
